CLAIM

The ornamental design for a switching power adaptor with changeable plugs, as shown and described.

DESCRIPTION

FIG. 1 is a front view of the switching power adaptor with changeable plugs of my new design;

FIG. 2 is a rear view of the switching power adaptor with changeable plugs thereof;

FIG. 3 is a top view of the switching power adaptor with changeable plugs thereof;

FIG. 4 is a bottom view of the switching power adaptor with changeable plugs thereof;

FIG. 5 is a left side view of the switching power adaptor with changeable plugs thereof;

FIG. 6 is a right side view of the switching power adaptor with changeable plugs thereof;

FIG. 7 is a top perspective view of the switching power adaptor with changeable plugs thereof; and,

FIG. 8 is a bottom perspective view of the switching power adaptor with changeable plugs thereof.
